UNITED STATES PATENT OFFICE

139,022

DESIGN FOR A TWO-UNIT LOCOMOTIVE BODY

John Markestein, North Riverside, Ill., assignor
to General Motors Corporation, Detroit, Mich.,
a corporation of Delaware

Application August 17, 1944, Serial No. 114,920

Term of patent 14 years

(Cl. D66—1)

To all whom it may concern:

Be it known that I, John Markestein, a citizen of the United States, being a resident of North Riverside, county of Cook, State of Illinois, have invented a new, original, and ornamental Design for a Two-Unit Locomotive Body, of which the following is a specification, reference being made to the accompanying drawing, forming a part thereof.

In the drawing:

Fig. 1 is a side elevational view of a two-unit locomotive body showing my design.

Fig. 2 is a view similar to Fig. 1 but showing the opposite side of the two-unit locomotive body.

Fig. 3 is a front elevational view thereof.

The appearance of the rear end portion of the two-unit locomotive body design is conventional.

I claim:

The ornamental design for a two-unit locomotive body, substantially as shown and described.

JOHN MARKESTEIN.
